United States Patent Office.

J. K. SEEM, OF CANTON, PENNSYLVANIA.

Letters Patent No. 73,127, dated January 7, 1868.

IMPROVEMENT IN CLOCK-CALENDARS.

The Schedule referred to in these Letters Patent and making part of the same.

TO ALL WHOM IT MAY CONCERN:

Be it known that I, J. K. SEEM, of Canton, in the county of Bradford, and State of Pennsylvania, have invented a new and useful Improvement in Clock-Calendars; and I do hereby declare that the following is a full, clear, and exact description thereof, which will enable others skilled in the art to make and use the same, reference being had to the accompanying drawings, forming part of this specification.

This invention relates to a new and improved arrangement for showing the month, the day of the month, and the day of the week, on a clock-face; and it consists in an arrangement of wheels which are revolved by the movement of the clock, whereby a perpetual calendar is produced, and which is read on the face of the clock, as I will proceed to describe.

Figure 1 represents the back side of the face of the clock, showing wheels which are attached to it, by the revolution of which the letters and figures of the months and days are exhibited through apertures in the face.

Figure 2 shows the clock-face with the apertures and names of the month, day of the month, and day of the week.

Figure 3 is a cross-section of fig. 1, through the line *x x*.

Similar letters of reference indicate like parts.

The names of the months are placed or printed on two disk-wheels, which lie one over the other. Through the outer disk there is a hole corresponding in size and form with that through the clock-face. Each wheel contains a portion of the name of the month, as neither one could contain the whole unless greatly enlarged. These disk-wheels are set by hand at the bottom of the face, at *a*, so that the name of the month is shown through the clock-face, as represented. The outer disk is held in place by the stop at *c*. These disk-wheels are at *A*, and are seen in dotted lines in fig. 2. *B* is a wheel, which is placed on the clock-spindle, and which revolves with the hour-hand. *e e* are two pins in this wheel, which engage with the cogs or fingers on the day-of-the-week wheel *C*. There are seven of these cogs, one for each day of the week, and they engage with the cogs of the day-of-the-month wheel *D*, and turn it, one cog for every day. The wheel *D* has the nine digits and the 0 upon it. Between this wheel and the clock there is a plate, seen in dotted lines, at *d*, through the drawing, fig. 2, having the figures 1, 2, and 3 upon it. The plate *d* is also provided upon its inner side with four projections, *b'*, near its centre, as shown in fig. 1, and is turned one figure every ten days by a projection, *a'*, upon one side of the wheel *D*, engaging with the projections *b'* upon the plate *d''*. The wheel *D* has ten cogs upon it, so that any number of figures from 1 to 31 can be shown by the wheel and the plate, as the number 15 is shown in the drawing. When the wheel *D* shall have made one revolution, the projection *a'* will engage with one of the projections *b'* upon the plate *d*, and the latter will be moved so as to present the figure 2 through the opening in the face of the dial. The figure 2 will then be opposite the naught (0) on the wheel *D*, and the day of the month indicated will be 20. The plate *d* is held in place by a spring, *f*, seen in fig. 1. *g* is a spring, which holds the wheel *C* in place, working upon the serrated edge of a disk, *J*, which is fast to the wheel. *h* is another spring, which bears against the wheel *D*. The wheel *C* revolves on a pivot, which is attached to the clock-face. The pivot of *D* is attached to an arm, which raises its centre from the face, and out of the way of the plate *d*, which plate is revolved within the rim of the wheel, as seen in the drawing. *i i* are apertures through the face of the clock, through which the wheels *C* and *D* may be moved by hand when desired.

By this method of construction and arrangement, I am enabled to add the calendar, as herein shown and described, to old clocks, by merely adding a new face, and it is more particularly for this purpose that the improvement is designed.

What I claim as new, and desire to secure by Letters Patent, is—

The construction and arrangement of the wheels *B C D*, and the plate *d*, substantially as described for the purposes set forth.

J. K. SEEM.
